FREE PUMPING SYSTEM

Roger W. Schoen, Mineral Wells, Tex., and Ralph B. Tilney, Clayton, Mo., assignors to Alco Valve Company, St. Louis, Mo., a corporation of Missouri

Application April 5, 1954, Serial No. 420,854

10 Claims. (Cl. 103—46)

The present invention relates to a free pump system. Free pumps are particularly useful in connection with deep well pumping operations. There are pumps available that are adapted to be lowered to the bottom of the well and there be operated by means of hydraulic pressure conditions developed in a column of power oil piped down from the surface. Such hydraulic pumps do not require a long mechanical pump rod reciprocating throughout the length of the well.

The so-called free pump was developed as an improvement in the hydraulic pumping arrangement because, in order to remove the hydraulic pump from the well, the entire power oil tubing had to be drawn out of the well to bring the pump to the surface. The free pump is not rigidly attached to the bottom of the power oil tubing, but rather is made to be slidably through tubing to the bottom of the well by gravity assisted, as may be necessary, by application of hydraulic pressure above it. Conversely, it is made slidably back from the bottom of the well to the surface by a reversal of hydraulic pressure conditions in the well so that relatively high pressure acts beneath the pump to drive it upwardly to the surface. Thus, a free pump is not mechanically bound to the bottom of the well, nor mechanically bound to a long string of tubing which must be drawn out of the well before the pump can be removed.

In a free pump arrangement, there must be two separate conduits for oil, one to conduct the power oil down to the pump and the other for conducting the production oil plus exhaust power oil back to the surface. Heretofore, the free pump arrangements have had to have the pump reciprocable in the power oil tube, as distinguished from the production oil tubing. This is to reverse normal hydraulic pump practice, and it requires the high pressures to be applied to the large tubing, and the larger volume of liquid to be transmitted in the relatively smaller tubing. This reversal is inefficient for obvious reasons.

One of the objects of the present invention is to provide a free pump system in which the pump is in the relatively larger production oil tubing rather than in the small power oil tubing, with the increased efficiencies resulting therefrom. To this end, the present pump system includes a free pump and a four-way valve at the surface connected into the power oil and production oil tubing so that it can reverse the piping of the power oil and production oil. By this ability to reverse the application of pressure to the two columns of oil, pressure can be applied to the production oil column and the power oil can be relieved of the pressure. There is a valve arrangement associated with the pump itself that acts responsively to temporarily shifting of pressure to the production oil column by means of the four-way valve, to cause power oil to be applied beneath the pump so as to lift the pump out of the well.

The broad improvement represented in the previous paragraph is supplemented by numerous improvements in the specific mechanism involved, as will appear from the description to follow.

In the drawings:

Figure 7 is a transverse section on the line 7—7 of Figure 1;

20 Figure 8 is a transverse section on the line 8—8 of Figure 1;

Figure 9 is a fragmentary vertical section of the part shown at the bottom of Figure 1, with the valve locked down; and

25 Figure 10 is a diagrammatic view of the pumping system, broken away in sections so as to foreshorten it.

In the drawings, a well tubing 10 is represented, it being adapted to encase a well. Within the lower part of the tubing 10, near the bottom of the well, there is an offset shoe fitting 11 that is externally threaded at 12 to receive a mud anchor, and that is internally threaded at 13 to receive a gas anchor, which parts form no part of the present invention. The shoe 11 has the foregoing parts arranged concentrically with the tubing 10, and it has an upper, internally threaded sleeve 14 that is offset from the center of the tubing.

30 35 The sleeve 14 of the shoe 11 is threaded onto the lower end of a standing valve barrel 16 into which is fitted a standing valve generally designated at 17. The standing valve includes a headed plug 18 slidably in the barrel 16 to descend and rest upon a shoulder in the upper part of the shoe 11. The reduced end of the plug 18 is externally threaded so as to receive a cage 19 that has appropriate external packing sealing it within the valve barrel 16. The cage 19 contains the check valve 20 in a medial portion that has vertical slots. The valve can seat upon a valve seat 21 when it is down in the lower part of the cage. The valve 20 can lift upwardly as far as a stop 22 that is part of the upper portion 23 of the cage 19, to permit flow of oil upwardly through the plug 18, the valve seat 21, the slotted cage and the upper fitting 23. The top fitting 23 is ported as at 24 and has a spearhead 25 projecting upwardly so that it may receive a pulling tool, as is known in the art.

40 45 Above the standing valve 17 there is a sealing tube 26 slidably fitted within the barrel 16 and provided with suitable external packing as illustrated.

50 55 The barrel 16 is externally threaded at its upper end and attached into a coupling 30. The upper end of the coupling 30 is, in turn, threaded to receive the lower end of a barrel 31. The barrel 31 is an outer barrel in which a production unit 32 is supported. That production unit 60 comprises a hydraulic motor and a pump, such as a sucker rod pump, operated by the motor, with appropriate check valves to control the direction of flow of the oil. See, for examples, applications Serial No. 373,955, filed August 13, 1953, and Serial No. 384,732, filed October 7, 1953.

65 70 The inner diameter of the barrel 16 is less than that of the barrel 31. This difference is important because, as will appear, it provides a hydraulic pressure area differential used in driving the assembly to the surface. As illustrated, the production unit 32 is threaded onto the upper end of the spacing tube 26 so as to provide a

continuous passage from the valve 17 into the production unit 32. It will be understood that the production unit delivers production oil into the space 33 between the outer barrel 31 and the inner barrel 32.

The upper end of the outer barrel 31 is connected into a coupling 34; and the upper end of that coupling is connected to the tubular housing 35 of a control valve which forms a particular part of the present invention. The upper end of the housing 35 is connected into a coupling 36 that, in turn, is connected into an upper outer barrel 37. Suitable connections are provided so that the upper tubing 37 will be continuous to the surface. It will conduct the production oil to the surface as will appear.

The control valve housing 35 has a lateral offset 38 that receives the lower end of power oil tubing 39. This power oil tubing also is continuous to the surface.

As shown in Figure 2, the upper end of the production unit barrel 32 receives a threaded end of a nipple 40, and that nipple, at its upper end, is threaded into the lower end of a cage 42 that is slidably fitted within the housing 35. This cage 42 has an outer diameter greater than that of the production unit 32 and the sealing sleeve 26, and this difference is used in the hydraulic drive of the assembly to the surface. The cage 42 has a plurality of passages 43 circularly arranged around a center part 45 into which the nipple 40 is threaded. The production oil in the space or passage 33 outside the production unit barrel and within the outer barrel 31 can be conducted through the passages 43.

The center portion 45 of the cage 42 also receives the lower end of a tube 47 that is slidably inserted into a center bore of the part 45 to rest upon the top of the nipple 40, as illustrated in Figure 2. Appropriate packing is provided as illustrated. This tube 47 registers with the interior passage of the nipple 40 and correspondingly with the interior passage of the production unit 32. The upper end of the tube 47 projects through and above an enlarged opening in the top of the cage 42. This opening is large enough to receive a sleeve 48 and to leave a space between the interior of the sleeve and the exterior of the tube 47.

The sleeve 48 is threaded into the upper end of the cage 42. It has a shoulder 49 engageable over a packing ring 50 to clamp the packing against the top of the cage 42. The packing 50 bears sealingly within the interior of the housing 35. The upper part of the sleeve 48 has a flange 51 above which it is externally threaded to receive the lower end 53 of an upper inside barrel 54. The lower part 53 of the inside barrel 54 has a slidable fit within the casing 35. Similarly, the upper part 55 of the barrel 54 has such a fit within the casing; but the intermediate portion has a reduced outside diameter. The portion 55 receives the lower flanged and threaded end of a packing retainer 56 that is surrounded by packing elements 57 and 58 which provide for a slidable fit within the casing 35. The casing is of uniform internal diameter. The upper end of the packing 58 is confined by a packing ring 59 threaded onto the packing retainer 56. The upper retainer 59 has a spearhead 60 projecting from its upper end, to receive a pulling tool. Figure 4 illustrates that the spearhead 60 is on a shaft that is connected by three connectors 61 to the lower part of the fitting, this providing for communication from the interior of the packing retainer 56 to the upper part of the tubing 37.

The lateral projection 38 on the valve casing 35 provides an elongated passage 65, the upper end of which connects into the lower end of the power oil tubing 39. The passage 65 also registers and is substantially coextensive along the axis with the reduced part of the inside barrel 53 so that there is communication all the way around that barrel.

Returning to Figure 2, the tube 47 has its upper end somewhat enlarged and provided with packing so that it

may slidably fit into a central tubular part 66 of the inside valve barrel 54. The central part 66 projects downwardly into the upper end of the packing ring 48, as appears at the top of Figure 2. The interior of the tube 47 thereby communicates into a bore 67 along the axis of the member 55. This bore 67 registers with a lateral passage 68 shown at the bottom of Figure 1 and in Figure 7. This passage 68, in turn, connects through the reduced part of the control valve barrel 54, and, as illustrated, registers with the passage 65 leading to the power oil tubing 39. This lateral passage 68 is controlled by a valve, as will appear.

The lower part of the barrel 54 has a series of vertical bores 70 circularly arranged around the center bore 67 (Figures 1, 7 and 8). Each of these passages 70 connects at its upper end with a radial passage 71 that connects into the bore 67.

As shown in Figures 1, 5 and 6, there is a plurality of radial passages 73 spaced above the radial passages 71. Each passage 73 registers with the bottom end of a vertical bore 74. The bores 74 are circularly disposed around the central bore 67 and extend upwardly to the top of the inner barrel 53, at which point they open into the interior of the packing retainers 56-59, and ultimately into the interior of the production oil tubing 37.

The axial bore 67 in the control valve housing 54 is adapted to receive the upper land of a valve generally indicated at 79. It has a lower land 80 slidably within the passage 67. Below the land 80 there is a downwardly projecting pin 81 provided with circular grooves, and a point at the bottom thereof, all for purposes to appear. A valve stem 82 projects above the land 80 and connects to an upper land 83 to space them as is indicated in Figure 1.

The upper end of this valve 79 is connected to a stem 84 by a threaded collar 85. By this means, there can be some axial adjustment of these parts. The upper end of the stem 84 has an enlarged head 86 fitting slidably within the bore 76. It acts as an abutment for a valve spring 87. The valve spring extends downwardly and rests at its lower end against a shoulder in an upper, enlarged part 88 of the bore 67, which enlarged part forms a pressure chamber as will appear.

The head 86 of the flanged stem 84 is provided with angular ports 89 that open into a central recess in the top of the head. The recess, in turn, registers with a corresponding central bore in a plug 90 that is threaded in to the upper end of the inside barrel 54. The plug 90 is provided with a central bore of varying diameters as indicated. This bore is closed at its top by a tubular plug 91 that has a check valve seat at its lower end. The ball check valve 92 coats with this seat, being urged upwardly by a flanged member 93 acted upon by a compression spring 94, as is indicated in Figure 1.

By the foregoing arrangement, the control valve 79 is normally held upwardly with its head 86 against the plug 90. The valve 79 may be forced downward against the spring 87, and a retaining device is provided so that the main valve 79 can be held in a lower position. To this end, as shown particularly in Figures 8 and 9, the bottom of the reduced intermediate part of the control valve barrel 54 has a radial bore 96 connecting through to the axial bore 67. The radial bore receives a reciprocable retainer plug 98. This plug 98 is of varying diameters so that its inner end projects into the bore 67 through a reduced inner end of the radial bore 96; and the inner end of the plug 98 is provided with vertical notches 100 corresponding to the notches on the depending pin 81 on the valve.

Within the larger parts of the bore 96 the plug 98 is shaped to be surrounded and acted upon by a coil spring 101 that urges the plug outwardly in the manner illustrated. There is a retaining member 102 threaded into the outermost part of the plug receiving bore 96 to hold these parts in place. The plug 98 has an axial passage 103, and the retaining cap 102 has a larger hold 104 so

that certain amounts of liquid may flow through these parts. Also, there is a vertical bore 105 connecting down into the spring chamber of the bore 96 for a purpose to appear. The upper end of the passage 105 opens into one of the transverse passages 73.

There is also a bleed port 106 that extends upwardly through the upper land of the valve 79 for a purpose to appear.

When in position, the well tubing 10 is in place and the main pump tubing is inserted down through the well casing 10. That is to say, the offset shoe 11 is in the bottom of the well with the mud anchor and gas anchor attached thereto and positioned in the conventional manner. The assembly, including the valve 17, is located in the bottom of the tubing 16, and the entire string consisting of the tubing 16, the coupling 30, the tubing 31, the coupling 34, the valve housing 35, the coupling 36, and the various lengths of tubing 37 are in place and extend to the surface. Similarly, the power oil tubing 39 is in place and extends to the surface.

At the surface there is piping 371 (Figure 10) connecting the production tubing 37 to the four-way valve 110, and likewise there is piping 391 connecting power oil tubing 39 to the four-way valve. Power oil is brought to the four-way valve by piping 392, and production oil is conducted to tanks by piping 372. The piping 392 connects to a source of hydraulic pressure in order that the power oil may be subjected to pressure conditions. This is explained in the copending applications referred to, and is conventional to the hydraulic type of the well pump.

In the present case, the four-way valve is designed so that it normally will connect the piping 392 and the source of hydraulic pressure with the power oil tubing 39, and will connect the piping 372 with the production oil tubing 37; but it may be reversed so as to connect piping 392 and the hydraulic pressure source to the production oil and to connect the power oil tubing 39 to the tanks. Consequently, although ordinarily the oil in the power oil tubing 39 is subjected to pressure continuously or intermittently in accordance with the type of pump and motor employed, this source of pressure may alternately be applied to the production oil in the tubing 37.

Operation

Prior to inserting the pump into the well tubing, the tube 26 is connected to the production unit 32, and the production unit 32, in turn, is connected to the nipple 40. That nipple 40 is connected into the bottom of the cage 45. The packing retainer 48 and the packing 50 are connected to the nipple 40 as indicated. The tube 47 is inserted and the control valve housing 54 is connected to the packing retainer 48. Above this the packing members 56 and 59 are connected together so as to retain the packing rings 57 and 58, and the packing assembly is secured to the housing 54.

The foregoing, therefore, provides for the attachment together, prior to their introduction into the previously mentioned pump tubing, of the various components of the pump including the production unit and the reversing valve mechanism. With appropriate tools, such as a grapple engageable with the spearhead 69, the foregoing assembly is then inserted into the tubing 19 and lowered below the surface.

The four-way valve 110 may be operated then to connect the power oil supply into the top of the tubing 37. This will apply pressure to the oil in the tubing 37, down past the legs 61 and into the interior of the packing retainers 59 and 56. It then will be applied down into the passages 74. However, it also is applied downwardly against the check valve 92, displacing it so as to fill the interior of the pressure chamber 88 with high pressure oil. Therein the net area downwardly is greater than the effective unbalanced net area upwardly so that this hydraulic pressure forces the valve 79 down to the position illustrated in Figure 9, which is such that the upper land

83 cuts off the lateral passages 73 while the lower land 80 moves down below the lateral passage 68.

With the valve 79 in that position, the communication from the production tubing 37 downwardly past the valve 5 is prevented. Consequently, hydraulic pressure applied to the oil in the tubing 37 forces the whole assembly downwardly. Any fluid pressure below the assembly may escape upwardly past the lowered valve 79, into the tubing 39, wherein there is only gravity head pressure.

10 The descent of the pump and valve assembly to the bottom of the well is completed when the member 26 comes to rest on the top of the valve cage 19. Thereupon, the parts occupy the positions illustrated in Figures 1, 2 and 3 save for the fact that the valve 79 is down.

15 From the practical standpoint, the pump should be lowered into the pump tubing with oil in the tubing.

When the foregoing is accomplished, the four-way valve 110 is turned to relieve power oil pressure from both tubing 37 and tubing 39. When the four-way valve is

20 operated to relieve the power oil pressure from the top of the valve 79, the spring 87 becomes sufficient to cause the valve 79 again to rise. The check valve 92 seats, but the spring nevertheless can cause the oil within the pressure chamber 76 to be expelled through the bleed passage 106 down through the upper land 83 of the valve. Consequently, the valve will rise to the position shown in Figure 1.

25 The foregoing requires only a brief interval. The operator waits an appropriate time to permit the valve 79 to rise, and then shifts the valve 110 to connect power oil pressure to the tubing 39, and to connect the production tubing 37 to the tubing 372.

30 In the position shown in Figure 1, the power oil from the pipe 39, which is under greater pressure, is connected 35 down through the passage 65 of the lateral extension 38 on the casing 35, thence through the lateral passage 68 to the interior valve bore passage 67 below the valve 79. Power oil continues down through the tube 47 and the nipple 49 to the interior of the upper side of the production unit 32. From the other patent applications referred 40 to, it will be understood that the power oil is introduced into the top of a pump motor in which there is an appropriate reversing valve mechanism that alternately admits this power oil pressure, and then admits production oil pressure to the upper side of a piston system while maintaining power oil pressure constantly on the lower side of the piston, which correspondingly is caused to ascend and descend, thereby operating the pump. (Of course, other hydraulic pump systems are known, which operate 45 by valving the high pressure oil and the lower pressure production oil into a hydraulic pump motor.)

50 By this pumping action, production oil is drawn up from the bottom of the well past the valve 20 into the spacer 26. From this spacer it is drawn into the pump 55 and then is expelled into the production oil space 33 between the unit 32 and the tubing 31. The pump forces the production oil to the top of the space 33 whence it moves upwardly through the outer series of passages, including the passages 43 in the cage 42, and thence up 60 within the packing retainer 48, around the outside of the tube 47. It moves into the lower part 53 of the member 54 and thence by way of the passages 70 to the transverse passages 71. With the valve 79 down, the lower land 80 thereof causes this production oil to be admitted upwardly to the transverse passages 73, the vertical passages 74, the interior of the packing retainer 56—59, and on upwardly to the production tubing 37.

65 As the pump continues to operate, it forces the production oil, plus the used power oil, up through the tubing 37 as indicated.

70 When it is desired to bring the pump assembly to the surface, the four-way valve 110 is caused to reverse the connections to apply the pressure to the oil in the tubing 37 and to relieve the pressure on the tubing 39. This 75 pressure will cause the check valve 92 within the plug 90

to open so that high pressure will be introduced into the pressure chamber 88 above the valve 79. Again, the valve 79 will descend until it reaches the position illustrated in Figure 9. At this time the locking plunger 98 is still in its retracted position under the influence of the spring 101. When the valve 79 is down, the power oil tubing 39 connects down by way of the passage 65, the transverse passage 68, into the transverse passages 71, the vertical passages 70, and thence downwardly throughout the production oil space 33.

With the valve 79 in its lower position, the production oil tubing 37 is cut off from communication to below the control valve housing 54 at the upper land 83 of the valve 79 which is disposed across the transverse passages 73.

After the four-way valve has been held in the foregoing position for a period long enough to insure that high pressure applied to the tubing 37 has forced the valve 79 fully down, the four-way valve is restored to its original position and the pressure is applied to the oil in the power oil tubing 39, whereas the production oil tubing 37 is relieved of pressure so that the pressure therein is merely the hydrostatic head from the surface down to the pump.

As soon as pressure again exists on the power oil tubing 39, this pressure is delivered through the passage 65. The lower end of the reduced portion of the housing 54 receives the plug 102, so that fluid from the passage 65 may always flow into the port 104 shown in Figures 8 and 9, to the head of the locking plug 98. Owing to the fact that the hole 104 has considerably less resistance to flow than does the bleeder port 103 through the plug 98, the plug will be forced inwardly against the spring 101 and will be caused to bring its grooves 100 against the grooves in the depending pin 81 on the bottom of the valve. The power oil pressure will continue to be applied to the plug 98, holding it in locking position so that the valve 79 is maintained in its lower position.

During the interval between the time that the four-way valve 110 relieves the pressure on the top of the valve 79 and the time that the locking plug 98 can be forced into locking position, the valve 79 is restrained into its lower position by hydraulic dampener action. In forcing the valve down, the pressure chamber 88 is filled with oil which passed the check valve 92. As soon as the power oil pressure was relieved in the tubing 37, the spring 87 tended to force the valve 79 upwardly. Such upward movement reduces the size of the pressure chamber 88 so that oil must be expelled therefrom to enable the valve to rise. However, the check valve 92 seats under these conditions so as to prevent free escape of oil from the pressure chamber 76, leaving only the restricted passage 106 for escape of oil therefrom. The bleeder passage 106 is so small that the flow therethrough permits only a very slow ascent of the valve 79 and no substantial movement of the valve will have occurred in the interval between the shifting of the check valve 92 relieving the pressure from the tubing 37 and to applying pressure to the tubing 39. The multiple grooves on the pin 81 and the plug 98, however, will insure a locking action for several positions of the valve 79, and thus permit a certain tolerance in the foregoing action.

By the foregoing action, the control valve 79 is depressed and locked down to remain down as long as pressure continues in the tubing 39.

When the power oil pressure is applied with the valve in its lower position, such pressure is blocked by the lower land 80 of the valve 79 from its usual inside passage to the production unit, and instead is delivered via the passages 71 and 70 to the outer passages that normally receive production oil. It is transmitted down outside the production unit 32. It is sealed by the packing rings around the sealing sleeve 26, from passing below this sleeve.

The sleeve 26 is of less diameter than the housing 54, so that there is a net area differential producing an upward net hydraulic force. Therefore, pressure conditions as stated cause the entire assembly of the sleeve 26, the production unit 32 and the valve housing 54 to be forced upwardly, they being all attached together.

Presently, the assembly will be driven upward until the retainer 102 is above the top of the passage 65. Prior to this, the lower edge of the cage 42 will ascend above the lower end of the passage 65, so that power oil pressure continues to force the assembly upward. And it becomes unnecessary for the valve 79 to remain down, so that relief of pressure on the plug 98 and outward movement of the plug is of no consequence. However, pressure normally backflows up through the cage, the passages 76, 71 and 68 to maintain pressure against the plug 98.

By the foregoing means, the assembly is forced to the surface hydraulically. And the result is accomplished without requiring the pump to descend in the power oil tubing. Therefore, that tubing may be small, as is desirable.

What is claimed is:

1. A free pump apparatus including a housing having a through passage and a lateral passage connecting into the through passage between the upper and lower ends thereof, the upper end of the through passage being connectible with production oil tubing leading to the surface and the lower end being connectible to like tubing to enclose a production unit at the bottom of the well, said tubing and the through passage providing a uniform passage to the surface; power oil tubing connecting from the lateral passage of the housing to the surface; a production unit within the lower production oil tubing with a sealing sleeve attached to the bottom thereof, the sleeve having a diameter less than that of the production oil tubing and an extension below the lower production oil tubing into which the sealing sleeve slidably fits and substantially seals; a check valve in the extension below the sealing sleeve, the production unit having a size less than that of the through passage to provide a fluid passage between itself and the tubing; a valve barrel having a slidably fit within the through passage and extending above and below the lateral passage of the housing with sealing means above and below that passage sealing between the housing and the barrel; a valve in the valve barrel; an upper passage connecting down from the top of the barrel to the valve, the passage opening upwardly to the production oil tubing; two lower passages below the valve, comprising a lower production oil passage opening downwardly to the space around the production unit, and a lower, separate power oil passage connecting into the production unit; a side passage into the valve barrel for connection with the lateral passage of the housing, the valve having a first position connecting the upper passage with the lower production oil passage while also connecting the side passage with the lower power oil passage, and the valve having a second position connecting the side passage with the lower production oil passage and closing the upper passage and the lower power oil passage; fluid pressure means to move the valve from the first position to second position responsive to high pressure applied to the production oil passage; yieldable means normally urging the valve into first position and yieldable only to pressures above normal head of the production oil passage; and means to retain the valve in second position against action of the yieldable means, so that the power oil introduced into the lower production oil passage may act upwardly on a larger area than downwardly and drive the pump assembly upwardly from the well, the lateral passage having connection with the side passage throughout an axial distance sufficient to permit the lateral passage to connect below the lower housing sealing before the side passage moves beyond the upper end of the lateral passage.

2. In a free pump: an assembly comprising a production unit and a valve, the assembly being sized to pass downwardly through well tubing to the lower end of a well, the assembly having a side passage for connection with a power fluid tube for introducing power fluid into the production unit to operate the pump and drive production fluid out the well tubing, the assembly having a lower end of reduced diameter having a sealing fit with well tubing below the previously mentioned tubing at the lower end of the well, and the assembly having a sliding, piston-like fit into the well tubing above the sealing fit, the assembly having a larger size above the sealing fit so as to provide a space having an area differential such that hydraulic pressure can drive the pump upwardly, a valve in the assembly movable to connect the power oil tubing into the area-differential space, and means in the assembly to move the valve to enable power oil to drive the pump assembly from the well.

3. The combination of claim 2, wherein the valve moving means comprises a fluid power means resistant to normal hydraulic pressures in the well tubing, but movable when extra high pressure is applied thereto, and means to hold the valve in the moved position.

4. The combination of claim 2, wherein the valve moving means comprises a hydraulic pressure chamber and a piston therein subjected to pressure in the well tubing above the assembly, yieldable means urging the piston against such pressure and having strength to hold it against normal hydraulic pressure therein, and means to hold the valve in its moved position.

5. The combination of claim 4, wherein the means to hold the valve includes a hydraulically operated lock having a hydraulic plunger driven to valve-holding position by predetermined hydraulic pressures in the power fluid tube.

6. The combination of claim 4, wherein the means to hold the valve includes a check valve permitting inflow of fluid into the pressure chamber and throttling means to permit outflow of fluid therefrom only at a slow rate.

7. A free pump apparatus for use in production fluid tubing, comprising: a pumping production unit having a barrel slideable in the production fluid tubing, the barrel having a through passage for transmitting production fluid from below the production unit to above it, and having a power oil passage extending laterally and opening through the side of the barrel for connection with a power oil supply, and extending downwardly for connection into the production unit, the barrel having sealing portions above and below the power oil passage that sealingly and slidably engage the walls of the tubing; control valve means in the barrel movable to first position to connect the upper and lower parts of the through passage, and also for connecting the lateral and downward parts of the power fluid passage, the valve means being movable to a second position to connect the lateral power fluid passage to the lower part of the through passage, to transmit power fluid to below the production unit and drive it to the surface; and means operable from

5 the surface to shift the valve means from first to second positions, comprising a four-way valve connected into the power fluid and production fluid tubings, so as to be operable to apply power fluid pressure to either tubing, and means responsive to application of power fluid pressures above normal production fluid pressures to cause the control valve means to shift.

8. A free pump apparatus for use in production fluid tubing, comprising: a pumping production unit having a barrel slideable in the production fluid tubing, the barrel having a through passage for transmitting production fluid from below the production unit to above it, and having a power oil passage extending laterally and opening through the side of the barrel for connection with 10 a power oil supply, and extending downwardly for connection into the production unit, the barrel having sealing portions above and below the power oil passage that sealingly and slidably engage the walls of the tubing; control valve means in the barrel movable to first position to connect the upper and lower parts of the through passage, and also for connecting the lateral and downward parts of the power fluid passage, the valve means being movable to a second position to connect the lateral power fluid passage to the lower part of the through passage, to transmit power fluid to below the production unit and drive it to the surface; and means operable from the surface to shift the valve means from first to second positions, said means including a pressure chamber, a check valve controlled passage admitting inflow of fluid from the tubing above the barrel into the pressure chamber but checking outflow, a piston-like member in said chamber and connected to the control valve means, yieldable resilient means urging the piston-like member to a first position, in which it positions the valve means in its first position, but yieldable to permit the piston-like member and the valve means to move to their second positions when the fluid pressure force produced in the chamber exceeds the force of the yieldable means, and a bleeder passage to provide restricted outflow of fluid from the chamber so that the piston-like member may return to its first position under action of the yieldable means when fluid pressure in the chamber is relieved.

9. The combination of claim 8 wherein the valve means has a latch surface, and the barrel has a plug slidably mounted through a wall to move into and out of latching engagement with the latching surface aforesaid, yieldable means urging the plug out of such engagement, a piston-like head on the plug subjected to pressure of the power fluid to be forced into such engagement, the inner end of the plug opening into the downwardly extending part of the power fluid passage so as to be subject to power fluid pressure on both ends except when the valve means is in its second position.

10. The combination of claim 9 wherein the plug has a bleeder passage through it.
